UNITED STATES PATENT OFFICE.

IRVING E. ASKE, OF DULUTH, MINNESOTA.

HEATER OR FUMER.

Application filed February 3, 1926. Serial No. 85,757.

My invention relates to heaters and fumers and has for one of its objects the provision of means for vaporizing fuming hydrocarbon fuel in the intake manifold of an internal explosion engine. With this and other objects in view, it consists of the structures, combinations and arrangements of parts hereinafter described and claimed.

In the drawings, Fig. 1, is a side elevation of a heating cell forming part of my invention. Fig. 2, is a top plan view of the same. Fig. 3, is a top plan view of a cover or hood for said cell. Fig. 4, is a side elevation of said cover. Fig. 5, is a side elevation of a pad or wick. Fig. 6, is a central vertical transverse section of said cover. Fig. 7, is a central vertical transverse section of said cell. Fig. 8, is a central transverse section of said cell, showing in section said wick wrapped longitudinally around the same. Fig. 9, is a central vertical transverse section of said cell, wick and cover. Fig. 10, is a side elevation, partly broken away, of an exhaust manifold and of an intake manifold, showing one of said cells, wicks and covers in longitudinal section, mounted upon said exhaust manifold and extending into said intake manifold. Fig. 11, is a central vertical longitudinal structure of my invention embodying electric heating means instead of exhaust gas heating means.

I am aware that attempts have heretofore been made to heat and vaporize incoming hydrocarbon fuel by means of hot plate, or common wall structures deriving their heat from the exhaust; but in these the exhaust cannot be run hot enough during idling speeds to be effective in vaporizing the excessive amount of raw gasoline which enters the intake manifold at such times. Therefore a considerable portion of the gasoline is not only wasted while driving slowly, or while the engine is idling, but part of it seeps into the crank case of the engine and operates to dilute the lubricating oil, causing waste of lubricating oil and frequently damage to the engine. In various attempts to make effective hot spots, the old principle of boiling the liquid fuel by passing it over and upon a hot plate has been used, but because of the rapidity with which the globules of fuel roll over and off of such plates, as well as because of insufficient temperature, sometimes due in part to the exposure of said plates to incoming cold air as well

as to liquid fuel, said structures do not give adequate service.

In the drawings, 1 is an exhaust manifold of any suitable form or structure, and 2, 60 is a fuel intake manifold of any suitable form or structure, having a depending reservoir or catch basin 2^a formed therein adapted to be closed at the bottom as hereinafter described. An aperture 1^a is 65 formed in the upper wall of said exhaust manifold below said catch basin, extending over which aperture and upwardly into said catch basin is a heating cell 3, preferably of copper, which cell is open at its bottom 70 and is closed on its top and sides and is adapted to receive hot exhaust gases through said aperture 1^a. Said cell has formed thereon a series of vertically directed grooves 3^a and ribs 3^b, and a horizontally disposed, outwardly directed annular flange 3^c at its lower edge.

Extending around the outer side of said cell is an absorbent element or wick 4, of any suitable refractory absorbent substance 80 or structure, preferably asbestos-felt or asbestos-fabric.

Extending over said cell and wick is a cover 5, open at the bottom and partly open at the top, as at 5^a, said top opening being 85 preferably in the form of an elongated slot. If desired, a screen of any suitable structure (not shown) may be formed in or extended across said slot. Said cover is provided at its bottom edge with an outwardly 90 directed, annular flange 5^b, and any suitable number of intake ports 5^c are formed in the side walls of said cover.

A gasket 6 of any suitable material, preferably asbestos, is preferably interposed between the flange of said cell and the flange of said cover. A similar gasket 7 is preferably interposed between the flange of said cell and the adjacent top wall or boss of said exhaust manifold, and a similar gasket 8 is 100 preferably interposed between the flange of said cover and an adjacent horizontally disposed outwardly directed flange 2^b formed upon the lower end of the side wall of said catch basin. It will be observed that said cover does not completely fill said catch basin, but is spaced a little from the side walls thereof and preferably extends slightly above said side walls, and also that the upper edge of said wick and said cell preferably 105 extend slightly above the side walls of said basin, so that the upper ends of said cover, 110

wick and cell will not be flooded by liquid fuel collected by said basin. It will be further observed that said cover with its flange and the interposed gasket, if any, operate to close the lower end of said basin, and said cover further serves to prevent portions of said wick from being drawn into the engine cylinders. In the structure shown in Fig. 11 the communication between the exhaust manifold and the heating cell is closed or omitted and the bottom of said cell 3, is closed in any suitable manner, as by an insulation plate 7^a, through which extends a binding post 9^b to which is electrically secured one lead 9^a from an electric resistance coil 9 positioned within said cell 3, which coil is grounded in any suitable manner, as by attachment to the walls of said cell. A lead 10 extends from said post to one side of a battery 11, and said cell or ground is also electrically connected in any suitable manner with the opposite side of said battery. A switch 12 is preferably interposed in the circuit of said battery and coil.

In operation, part of the hot exhaust gases flow up into said cell and heat the same to a high temperature. The heavy wet or liquid portion of the fuel drawn into the intake manifold from the carburetor by the action of the engine pistons, flows along the bottom of the intake manifold and drops into said catch basin from which it flows through said ports 4^b to and through said wick by which it is carried into contact with the heated sides of said cell, and successive films of said fuel are thereby fumed, the fumes passing up through the said grooves 3^a and out of said slot or opening in the top of said cover. Thus the fumes are protected from an overhead bath or flood of liquid fuel within the cover and from danger of recondensation thereby. It will be observed that the heating cell is protected from cold currents of air and that a high temperature of said cell can therefore be maintained; the amount of liquid fuel which would otherwise find its way into the crank case at low speeds is by the use of said invention greatly reduced, and the mileage per gallon of fuel used is increased.

I do not however desire to be understood as claiming said invention for use only in connection with automobile manifolds, or only with the special type of manifolds shown, since it appears to be available or adaptable for use for other purposes for which the vaporization or fuming of fuels or other liquids is necessary or desirable.

What I claim is:

1. The combination of a cell open at one side and closed on five sides, of an absorbent element surrounding said cell on four of the closed sides, and a hood for said cell and element, said hood being open on one of its sides for the extension of said cell

into said hood, said hood having an intake port formed in one of its sides for admitting liquid to said absorbent element, said hood having an exhaust port formed therein.

2. A heating cell comprising a shell open at its bottom and closed at its top and all of its sides, said shell having a plurality of ribs and grooves formed in its side walls.

3. The combination of a heating cell open on one side and closed on five sides, said cell having a plurality of ribs and grooves formed in the outer face of one of its walls, and an absorbent element applied to the outer faces of said ribs and extending across said grooves.

4. The combination of a conduit having a catch basin formed in its floor, said basin having an open bottom, a hood adapted to close the bottom of said basin and to extend up into said basin, said hood being spaced from the side walls of said basin, said hood being open at the bottom, a cell adapted to extend up into said hood and to close the bottom thereof, said cell being spaced from the side walls and top of said hood, said cell being open at its bottom, an absorbent element interposed between one of the sides of said cell and the opposing side of said hood, said hood having an intake port formed in one of its side walls and an exhaust port formed in its top.

5. The combination of a conduit having an aperture formed in its top, of a cell mounted on said conduit and extending over said aperture, said cell being open at its bottom and closed at its top and sides, the chamber within said cell being adapted to communicate with said conduit through said aperture, a hood extending over said cell and spaced from the top and sides thereof, and an absorbent element interposed in the space between said cell and hood, said hood having intake and exhaust ports formed therein.

6. The combination of a conduit having a catch basin formed in its floor, said basin having a concavo-convex bottom extending upwardly above the outer side walls of said basin, said concavo-convex bottom being adapted to form a hood for a heating cell, a heating cell comprising a concavo-convex shell extending upward into said hood and spaced from the side walls and top of said hood, and an absorbent element interposed between the side of said cell and the opposing face of said hood, said hood having intake and exhaust ports extending through its walls.

7. The combination of a fuel conduit having a catch basin formed therein, a conduit for hot fluids, an absorbent element positioned within said catch basin, and means for transmitting heat from said hot fluid conduit to said absorbent element.

8. The combination of a fluid conduit hav-

- ing a catch basin formed therein, an absorbent element adapted to receive fluid from said catch basin, a second fluid conduit, and heat transmitting means common to both of said conduits interposed between said second conduit and said absorbent element whereby said element is separated from said second conduit.
9. The combination of a fluid conduit, an absorbent element positioned therein and adapted to absorb fluid therefrom, a second fluid conduit, and heat transmitting means common to both of said conduits interposed between said second conduit and said absorbent element whereby said element is separated from said second conduit, said transmitting means being in contact with said absorbent element.
10. The combination of a fluid conduit provided with a catch basin intermediate of its ends, an absorbent element positioned in said basin and extending to the upper end of said basin, a second fluid conduit, heat transmitting means common to both of
- said conduits interposed between said second conduit and said absorbent element and extending to the top of said absorbent element in contact therewith, whereby said absorbent element is separated from said second conduit, said transmitting means being ribbed and grooved upon those portions of its sides which contact with said absorbent element.
11. The combination of a heating cell embodying a chamber with a radiation wall, means for heating the interior of said chamber and wall, a hood extending over said cell and spaced from said wall, and an absorbent element positioned in the space between said wall and said hood, said hood having an intake port formed therein adapted to admit moisture to said absorbent element, said hood having an exhaust port formed therein for the passage of vapor or fumes from said absorbent element.

In testimony whereof, I hereunto affix my signature.

IRVING E. ASKE.
